CLAIM

An ornamental design for a pendant substantially as shown and described.

DESCRIPTION

FIG. 1 is a front view of the pendant;

FIG. 2 shows a back view thereof;

FIG. 3 shows a right view thereof;

FIG. 4 shows a left view thereof;

FIG. 5 shows a top view thereof; and,

FIG. 6 shows a bottom view thereof.

The broken lines shown in the drawings represent portions of the pendant that form no part of the claimed design.
